(57) **CLAIM**

The ornamental design for a cabin hood for a vehicle with a telescopic lifter, as shown and described.

DESCRIPTION

FIG. 1 is a back-left side-top perspective view of a cabin hood for a vehicle with a telescopic lifter, showing the new design;

FIG. 2 is a left side view thereof;

FIG. 3 is a top view thereof;

FIG. 4 is a back view thereof;

FIG. 5 is a front view thereof;

FIG. 6 is a right side view thereof; and,

FIG. 7 is a bottom view thereof.

The broken lines showing a vehicle depict environmental structure that forms no part of the claimed design. The broken lines depicting portions of the cabin hood for the vehicle form no part of the claimed design.

1 Claim, 4 Drawing Sheets
